UNITED STATES PATENT OFFICE

HERMAN A. DE VRY, OF CHICAGO, ILLINOIS

DESIGN FOR A STEREOSCOPE

Application filed March 31, 1933. Serial No. 47,654. Term of patent 14 years.

To all whom it may concern:

Be it known that I, HERMAN A. DE VRY, a citizen of the United States, residing at Chicago, in the county of Cook and State of Illinois, have invented a new, original, and ornamental Design for Stereoscopes, of which the following is a specification, reference being had to the accompanying drawing forming a part thereof.

Figure 1 is a plan view of a stereoscope showing my new design;

Figure 2 is a front view;
Figure 3 is a rear view; and
Figure 4 is a side view.

I claim:

The ornamental design for a stereoscope substantially as shown.

Chicago, Illinois, March 18th, 1933.

HERMAN A. DE VRY.
